This invention relates to detector devices for microwaves.

Known detectors in which a conductor connected to a rectifier extends, parallel to the electric lines of force, into or through a wave guide, have the disadvantage that they cause a comparatively high reflection of the waves in the waveguide, and their sensitivity differs through a broad range of frequencies.

A microwave detector is known in which a rectifier is connected, in series with a capacitance forming substantially a short circuit with respect to microwaves, between opposite points of a circular aperture provided in a side wall of a wave guide. In this case the rectifier is arranged outside the waveguide proper and also outside the wall thereof. Said device may be made suitable for a broad range of frequencies by placing the rectifier in a suitably chosen cavity resonator outside the wave guide.

The present invention provides a very efficacious solution of the problem whereby the reflection coefficient of the detector may be lower than that of the known device.

A detector according to the invention employs a rectifier of a kind known per se. The rectifier is arranged inside a cylindrical shielding sleeve and has one pole connected to the shielding sleeve and its other pole connected to a concentric connecting pin. Such so-called coaxial rectifiers are sold commercially.

A detector according to the invention has an aperture provided at a corner in the wall of the wave guide. The rectifier is arranged so that the connecting pin extends in a longitudinal bore in the adjacent wall of the wave guide and at right angles to the edge of the corner. A series capacitance is formed by a narrow gap between the said shielding sleeve and further parts of the wall.

In order that the invention may be readily carried into effect, it will now be described in detail, by way of example, with reference to one embodiment thereof as shown in the accompanying diagrammatic drawing, in which:

FIGURE 1 is a cross-sectional view of a waveguide of rectangular section in which a detector is housed; and

FIGURE 2 shows a longitudinal section of the waveguide of FIGURE 1, taken along the plane II-II.

A conductive stub 2 for accommodating a detector 3 is provided at the left-hand upper corner of a wave guide 1. The stub 2 surrounds an aperture 20 in a waveguide wall 21 at the longitudinally extending junction between the wall 21 and the adjoining wall 10. Said stub may be omitted if the wall of the waveguide 1 itself is of sufficient thickness.

The rectifier 3 may be of a kind known per se and FIGURE 1 shows diagrammatically a cross-section thereof. The detector 3 includes a crystal diode 4, secured to the upper end of a connecting pin 6 which is held in a circular conductive shielding sleeve 8 by means of an insulating ring 7. A connecting spring 5 is connected to the sleeve 8 so that the terminals of the detector are formed by the pin 6 and the sleeve 8.

The pin 6 extends into a vertical bore 9 provided in the middle of the left-hand side wall 10 of the wave guide 1. The bore 9 extends in a transverse plane of the waveguide which passes through the aperture 20. The shielding sleeve 8 is situated in a circular aperture in the

stub 2 so that a narrow gap 11 exists between the sleeve 8 and the stub 2. This gap has a comparatively high capacity and substantially forms a short-circuit for microwaves. The gap preferably has a height equal to one quarter of the operational wavelength. The direct output voltage may be applied to an output circuit 22 connected between the sleeve 8 and the stub 2. Furthermore, as shown in FIGURE 2, an aperture 12 is provided in the left-hand side wall having a re-entrant portion 13 which serves as a stop for the ring 7 so that the position of the rectifier is fixed. The reentrant portion 13 of the aperture 12 is aligned with the aperture 20, so that the aperture 12 effectively consists of two apertures in the wall 10 on opposite sides of the aperture 20 with respect to the longitudinal direction of the waveguide.

As is well-known, due to the action of waves in a wave guide, currents flow in the side walls in a direction that is at right angles to the axis of the wave guide, that is to say vertical in the example shown, as indicated by arrows 14. However, the path of the wall currents is interrupted at the aperture 12 and these currents thus partly bend around the aperture and a portion flows through the rectifier 3, as indicated by arrows 15. The rectifier exhibits a certain impedance to the wall currents so that, if the aperture 12 is small, the path around the aperture is easier for the wall currents than that through the rectifier and thus only a very small current will flow through the rectifier. If the aperture is made larger, the detour around the aperture becomes larger and a greater proportion of the wall currents will flow through the rectifier. It has been found that, with suitable proportioning of the aperture, the direct output voltage of the detector may be made substantially constant through a broad range of frequencies.

In fact, if the aperture has a small length, the sensitivity of the detector usually decreases with increasing frequency, whereas just the reverse is the case if the aperture is comparatively long, so that the sensitivity is constant for a given intermediate length.

At high frequencies, the impedance of the rectifier is substantially determined by the capacitance between the connecting pin 6 and the shielding sleeve 8. In fact, the impedance of this capacitance is comparatively low with respect to the impedance of the crystal diode 4 itself. The latter impedance exhibits comparatively great differences from rectifier to rectifier because of structural differences. However, since the capacitance between the connecting pin 6 and the shielding sleeve 8 is comparatively constant the rectifier may be replaced by another in a simple manner without the frequency response curve substantially varying. On the other hand, two different detectors also exhibit substantially the same frequency response curve. This property may be employed by controlling the strength of a high-frequency oscillator by means of an output voltage from a first detector device and using a second detector device for measuring purposes. The output voltage of the second detector device may then be constant throughout the X band (8.2 to 12.4 Gc./s.) with a deviation less than 0.3 decibel. The alternating voltage set up across the crystal will usually be comparatively low so that the rectifier operates in the quadratic portion of its characteristic and the direct output voltage is proportional to the square of the field strength in the waveguide, that is to say proportional to the energy of the waves. The sensitivity is, for example, 10 mv./mw.

The detector according to the invention affords the considerable advantage that it does not substantially bring about reflection of the waves in the wave guide, for example at a standing wave ratio (V.S.W.R.) better than 1.01.

This is connected with the fact that, in the arrangement

in accordance with the invention, the supply conductors to the crystal are very short and hence have little impedance. The impedance of the detector is also comparatively low so that only a comparatively low voltage is set up across the aperture in the side wall and the configuration of the lines of force in the waveguide is also deformed but slightly.

As shown diagrammatically in FIGURE 1, the detector may alternatively be arranged in a partition between the waveguides, the wall parts 16 shown in broken line having to be regarded as belonging to a waveguide placed to the left of the waveguide 1. In this case the direct output voltage will be proportional to the sum of the wall currents in the two guides. The coupling between the two conductors is comparatively low (for example from -40 to 60 decibels) despite the aperture in the common side wall.

The longitudinal bore 9 need not fundamentally be formed in a short side of the wave guide and may alternatively be provided in a long side, and the detector device may alternatively be arranged at the corner of a ridge in a ridge waveguide.

What is claimed is:

1. Means for detecting high frequency oscillations in a waveguide, comprising a waveguide for conveying high frequency oscillations, said waveguide having a rectangular cross-section with first and second adjacent side walls, said first side wall having a first aperture at the junction of said first and second side walls, unidirectional current means having first and second terminals, means connecting said first terminal to said second side wall in the transverse plane of said waveguide which extends through said first aperture, capacitor means for coupling said second terminal to said first side wall in said plane, said second side wall having second and third apertures on opposite sides of said first aperture with respect to the longitudinal direction of said waveguide, whereby wall currents in said waveguide flow through said unidirectional current means, and output circuit means connected between said second terminal and said first side wall.

2. Means for detecting high frequency oscillations in a waveguide comprising a waveguide for conveying high frequency oscillations, said waveguide having first and second longitudinally extending adjoining walls, a cylindrical rectifier device of the type having a first cylindrical end portion comprising a first terminal and joined to a second cylindrical end portion of larger diameter, the second terminal of said rectifier device being on said second end portion, said waveguide having an aperture in said first wall adjacent the junction of said first and second walls, said second wall having a bore at said junction in the transverse plane of said waveguide passing through said aperture, said bore extending within said second wall substantially normal to the plane of said first wall, said first end portion being inserted within said bore, a conductive sleeve surrounding said second end portion and contacting said second terminal, means providing a capacitance between said sleeve and said first wall at said aperture, and output circuit means connected between said second terminal and said first wall.

3. Means for detecting high frequency oscillations in a waveguide comprising a waveguide for conveying high frequency oscillations, said waveguide having a rectangular cross-section with first and second adjoining walls, said first wall having a first aperture adjacent the junction

of said first and second walls, said second wall having second and third apertures adjacent said junction and overlapping said first aperture on opposite sides, rectifier means having first and second terminals, said first terminal being in contact with said second wall at said junction and between said second and third apertures, capacitor means connected between said second terminal and the edges of said first aperture, and output circuit means connected between said second terminal and said first wall.

5 4. The detecting means of claim 3, in which said capacitor means comprises a conductive sleeve surrounding said rectifier means and spaced from said first aperture, said sleeve being connected to said second terminal.

10 5. Means for detecting high frequency oscillations in a waveguide comprising a waveguide for conveying high frequency oscillations, said waveguide having a rectangular cross-section with first and second adjoining walls, said first wall having a first aperture adjacent the junction of said first and second walls, said second wall having apertures adjacent said junction and overlapping said first aperture on opposite sides, a stub extending from the edges of said first aperture normal to said first wall, said second wall having a bore between said second and third apertures and normal to said first wall, a coaxial diode having a pin comprising one terminal thereof inserted within said bore, a conductive sleeve surrounding said diode and being electrically connected to the other terminal thereof, said sleeve being within said stub and forming a capacitor between said stub and other terminal, and an output circuit connected between said other terminal and said stub.

15 6. A detecting means of claim 5, comprising a second waveguide, wherein said second wall is a common wall between said first-mentioned waveguide and said second waveguide, said first aperture extending through a wall of said second waveguide.

20 7. Means for detecting high frequency oscillations in a waveguide comprising a waveguide for conveying high frequency oscillations, said waveguide having first and second longitudinally extending adjoining walls, a coaxial rectifier device having first and second terminals on opposite ends of a cylindrical body, said first wall having an aperture extending therethrough at the junction of said first and second walls, said second wall having a bore extending from said junction at said aperture, said bore extending into said second wall substantially normal to said junction, said first terminal of said rectifier device being within said bore in contact with said second wall, said second terminal extending externally of said waveguide, capacitive means coupling said second terminal to said first wall externally of said waveguide, whereby wall currents in said waveguide flow through said rectifier device, output circuit means, and means connecting said output circuit means between said second terminal and said waveguide.
